UNITED STATES PATENT OFFICE.

THOMAS DARRINGTON SEMPLE, OF NEW YORK, N. Y., ASSIGNOR TO BLUE PETER
CIGARETTE CO., OF NEW YORK, N. Y., A CORPORATION OF NEW YORK.

CIGARETTE-CONTAINER.

1,098,178.

Specification of Letters Patent.

Patented May 26, 1914.

Application filed January 12, 1914. Serial No. 811,668.

To all whom it may concern:

Be it known that I, THOMAS DARRINGTON SEMPLE, a citizen of the United States, residing at New York, in the county of New York and State of New York, have invented 5 certain new and useful Improvements in Cigarette-Containers; and I do hereby declare the following to be a full, clear, and exact description of the invention, such as 10 will enable others skilled in the art to which it appertains to make and use the same.

My invention relates to improvements in cigarette containers, and it is intended to provide a hermetically sealed insulating container which, while extremely light, is of 15 sufficient stiffness for ordinary usage, and which is thoroughly hygienic, and may be cheaply made.

It is well known that cigarettes are apt to 20 deteriorate very rapidly if exposed to atmospheric influences, especially changes of air; and that they are also peculiarly susceptible to deterioration from high temperatures. Thus it has been found very difficult to provide 25 a suitable non-metallic package adapted to contain cigarettes and keep the same in proper condition when stored away on ship-board in the tropics, or in the heated portions of the ship.

30 My invention is intended to provide a non-metallic package which is especially adapted for use in the transportation of cigarettes and preserving the same in excellent condition, irrespective of the surrounding atmospheric conditions.

35 My invention will be understood by reference to the accompanying drawings in which the same parts are indicated by the same reference symbols throughout the 40 several views.

Figure 1 is a perspective view showing the package in central vertical section, parts being broken away; and Fig. 2 shows a section along the line 2—2 of Fig. 1 looking down.

45 A represents an ordinary cylindrical box made of papier mâché, or other suitable material, having the cover A', in which box the cigarettes X are inclosed.

50 B represents an outer cylindrical shell of pasteboard, or similar material, which is coated with paraffin so as to make it impervious to air or moisture. The opposite ends of this shell B are expanded somewhat from the interior, as at b°, to receive the

heads B', and the ends of the shell B are 55 then crimped over, as at b, and formed to hold the heads B' in place. The joint between the head and the crimp b is then preferably touched with melted paraffin, or other similar material, so as to form an air-tight 60 joint.

Between the inner box A and the outer shell B a centering and insulating strip is provided, comprising a paper sheet C to which a corrugated paper sheet C' is attached. The inner box fits snugly against the corrugations of this centering and insulating strip and thus the inner box is centered in the outer casing with an interposed layer of air between the two; thus protecting the cigarettes against change of temperature, but providing a sufficient air supply to maintain the cigarettes in normal condition and at the same time preventing the ingress of air or other gases. Moreover, by 75 this particular arrangement of hollow concentric cylindrical shells with an interposed resilient layer, the package is adapted to stand rough usage without breaking either shell, and, while extremely light, may be 80 very cheaply made.

In order to open the package, it will be sufficient to take out either one of the heads B', preferably the upper head, which may be done with an ordinary penknife, or any 85 suitable cutting tool.

By the use of the container herein described, cigarettes may be kept in perfect condition for long periods, even under conditions of atmosphere and temperature 90 which would ordinarily cause their rapid deterioration.

Having thus described my invention what I claim and desire to secure by Letters Patent of the United States is:—

1. A container for cigarettes comprising an inner cylindrical box; a strip faced with corrugated paper surrounding said box; an outer cylindrical paper shell, coated with paraffin or similar material to make it impervious to air, surrounding said strip, and having its ends crimped over; and heads beneath said crimped over ends, substantially as described.

2. A container for cigarettes comprising 105 an inner cylindrical box; a strip faced with corrugated paper surrounding said box; an outer cylindrical paper shell, coated with

paraffin or similar material to make it impervious to air, said shell having its ends internally expanded, and the edges crimped over internally; and heads mounted in said expanded portions and held beneath said crimped over edges, substantially as described.

In testimony whereof, I affix my signature, in presence of two witnesses.

T. DARRINGTON SEMPLE.
